UNITED STATES PATENT OFFICE

GEORGE E. NORRIS, OF COLUMBUS, OHIO

SLIP CLUTCH FOR VENDING MACHINES

Application filed December 1, 1928. Serial No. 323,170.

This invention relates to improvements in vending machines and has particular reference to vending machines of the type utilizing an inclosing cabinet wherein is provided a coin controlled mechanism for effecting the regulated release of various articles of merchandise from the cabinet. Further, this invention and application constitutes a continuation in part of the invention and disclosure set forth in my prior application filed March 14, 1928, Serial No. 261,202, now Patent No. 1,778,833 for improvements in vending machines.

With these and other objects in view which will appear as the description proceeds, the invention consists in the novel features of construction, combinations of elements and arrangements of parts hereinafter to be fully described and pointed out in the appended claims.

Coin controlled vending machines are subject to very considerable abuse when in service. The actuating elements are operated frequently with excessive muscular strength and in many instances are surreptitiously operated through the use of pliers, wrenches, or other tools, all of which results frequently in the placing of abnormal strains and stresses upon the operating parts of the vending machine, resulting either in the mechanical break-down of such parts, in the forcing of the machine so as to permit of the uncontrolled or unauthorized discharge of its contents or a part thereof, or other damage or undesired operation of the machine.

To avoid and correct these conditions, among others, it is the object of the present invention to provide an improved clutch or automatic release means whereby when a certain degree of pressure is applied to the actuating elements of the vending machine, above that normally required to successfully operate the machine under proper conditions, the said actuating elements are mechanically released or disconnected from the elements of the machine which are used to effect the release of the contents or merchandise contained within the machine, thereby preventing damage to the working parts of the machine or the forcing of such working parts to an extent whereby unauthorized release of the merchandisable contents of the machine is secured.

It is another object of the invention to provide a simple and effective form of clutch in a vending machine which is situated between a manually operated handle or crank and a

rotatable discharge device, the construction of the clutch being such that under normal conditions the operating handle or crank and the discharge device rotate in unison but when excessive pressures or forces are applied to the operating handle or crank the clutch member is frictionally released so as to maintain the discharge device in a stationary position and to prevent injury to the locking mechanism which normally co-operates with the discharge device to hold the latter in a normal position of operation.

With these and other objects in view which will appear as the description proceeds, the invention consists in the novel features of construction, combinations of elements and arrangements of parts hereinafter to be fully described and pointed out in the appended claims.

In the accompanying drawings:

Figure 1 is a front elevation of a vending machine formed in accordance with the present invention,

Figure 2 is a detailed vertical sectional view taken through the machine disclosing more particularly the merchandise receiving compartments and the rotatable discharge devices situated in the lower portions of each of the compartments,

Figure 3 is a vertical transverse sectional view taken through the vending machine, disclosing the rotatable discharge device and its operating handle together with coin controlled means for regulating the rotation of the discharge device,

Figure 4 is a detailed vertical sectional view disclosing more particularly the clutch mechanism comprising the present invention and illustrating the position of said mechanism in connection with the operating handle of one of said discharge devices,

Figure 5 is a vertical transverse sectional view on the line 5—5 of Figure 4,

Figure 6 is a similar view on the line 6—6 of Figure 4,

Figure 7 is a detailed view in rear elevation of the crank controlled locking mechanism for normally holding the discharge devices against rotation.

Referring more particularly to the draw-

ings, the vending machine illustrated therein comprises a casing 1. In the particular form of the invention here disclosed the casing is of box-like form and includes a front wall 2 provided with a transparent panel 3 through which the contents of the machine may be viewed.

Arranged within the casing 1 is a frame structure 4 which supports a plurality of vertically disposed transversely extending walls, the latter being relatively spaced to produce a plurality of vertically extending article or commodity receiving compartments 5. In this instance the compartments are constructed for the reception of tubular containers 6 in which the merchandise to be dispensed is received. It will be understood that the merchandise may be of any suitable character, such as articles of confection, wearing apparel, tobacco or any other suitable commodity. I prefer to use the cylindrical containers which are formed from cardboard ordinarily, since such containers simplify and improve the construction and operation of the dispensing or vending mechanism proper and possesses other advantages over the ordinary rectangular boxes or packages.

The containers are grouped in vertical order one above the other within the several compartments. Any suitable number of the containers are disposed within each compartment and as the containers are dispensed by the operation of the machine, they gravitate toward the bottom of the compartments 5, providing for gravitation feed toward discharging positions which is both simple and positive. The panel 3 permits the containers within each compartment to be viewed and enables the purchaser to note when any particular compartment is exhausted of its contents.

Arranged within the bottom of each compartment is a revolving holder or discharge device 7. Each of these holders, as shown in Figure 2, is of semi-circular form in vertical cross-section and of the diameter conformable to that of the container 6 which it dispenses. The lowermost container is received within the holder or discharge device and the trough may be rotated about its longitudinal axis to effect the discharge of such container. Preferably, each of the holders is of cast metal construction and in addition to its semi-circular body part, each holder embodies a substantially circular or disk shaped front and rear end walls 8 and 9 respectively. These walls are provided with axial journaling extensions which are received within aligned bearings provided in the front wall 2 and the frame structure 4, so that each holder will be mounted for rotary or oscillatory motion, since the movement thereof in any one direction is less than 360 degrees. Each trough or holder is provided, as shown in Figure 2, with a lug 10, which is adapted

to engage with a stationary finger 11, projecting downwardly from one of the compartment walls 5, and means are provided for normally retaining the lug 10 in engagement with the finger 11, as indicated in Figures 2 and 3. When in this position it will be seen that the containers 6 gravitate freely into and toward the holder 7 so that when the latter are rotated said containers will be removed from the compartments 5 and deposited into the discharge chamber 12, provided at the bottom of the casing 1 and below the holder 7.

The rear wall 9 of each holder is provided with a journaling stud 13 which is received within a bearing provided in the frame structure 4, and the outer end of the stud terminates in an enlarged head 14 with which cooperates mechanism of a coin controlled nature for admitting of rotation on the part of said holders but which mechanism normally restrains the holders against rotation. For purposes of disclosing the present invention it is deemed unnecessary to describe specifically the complete construction and operation of this mechanism, since the latter forms the basis of my aforesaid application and has been set forth in detail therein. Generally, it may be stated that the head 14 is formed with flat surfaces 15, with which engage locking fingers 16 which are pivotally mounted as at 17 on the frame structure 4. Normally, these locking fingers occupy fixed positions in close engagement with the surfaces 15, and for this reason rotary movement of the holders is precluded until the fingers 16 are released which is accomplished by the insertion of a coin into the machine. To require full rotary movement of the holders upon each operation the head 14 is also provided with ratchet teeth 18 with which engage a pivoted spring held detent 19, also carried by the frame structure 4 adjacent to the head 14. The outer end of the stud 13 carries a coil spring 20, one end of which is secured to the stud 13 while the other end engages with a bracket 21 carried by the frame structure 4. The normal office of this spring is to maintain the holders in the positions illustrated in Figure 2, with the lugs 10 thereof in engagement with the fingers 11. When a holder is released the spring 20 returns the same to the normal position described.

The cardinal feature of the present invention resides in the inclusion of a simple yet effective clutch mechanism as shown in Figures 4 to 6. It will be observed that each of the holders 7 is provided with an operating handle, crank, wheel or other device 22, which in this instance consists of a stem 23 having its outer end provided with an enlarged finger engaging web 24. It is preferable to provide this web with an arrow to indicate the direction in which the device should be turned to operate the machine.

The front wall 8 of each holder is formed

- to include a bearing sleeve 25 received for rotation within a longitudinal bearing 26 formed in the front wall 2 of the cabinet and arranged in axial alignment with the stud 13. 5 The sleeve 25 is provided with aligned openings 27, which are of such diameter as to partially receive a ball 28 received within a transverse bore 29 formed in the inner end of the stem 23, the ball 28 being pressed outwardly into engagement with the inner wall of the sleeve 25 by means of a spring 30, the latter being confined within the bore 29 between the inner portion thereof and the ball 28. 10 It will be seen that when a holder has been released by the coin controlled mechanism associated therewith, the said holder may be rotated by manually revolving the handle 22, and having normally sufficient frictional power exercised by the clutch mechanism to accomplish this operation. However, in the event that the holders are in a locked position and one endeavors to force the rotation thereof by the application of abnormal pressures 25 or forces applied to the operating handles the clutch mechanism will slip, since the ball 28 will be withdrawn into the tubular confines of the sleeve 25 and removed from the openings 27. It will be manifest therefore, that this release prevents excessive strains and stresses from being imparted to the locking mechanism or to the holders per se with the result that the life and usefulness of the machine is very greatly prolonged and repairs 30 are reduced to a minimum. It will be noted that the clutch mechanism is completely inclosed so that it cannot be reached from the exterior of the machine. Outward removal of the stem 23 from the sleeve 25 is prevented by providing said stem with an annular groove 31 in which is received a pin 32 carried by the sleeve 25. It will be seen that the present invention provides a simple and efficient protective feature particularly 35 adapted for use in connection with coin controlled vending machines whereby through the use of which the operating efficiency and life of such machines are very materially improved. 40 While I have described what I consider to be the preferred form of the invention, nevertheless it will be understood that various changes may be made in the construction from time to time without departing from the spirit and principles of the invention as the latter has been described and set forth in the following claims. 45 What is claimed is: 50 1. In an apparatus of the class described, 55 a clutch mechanism for connecting two rotatable elements, comprising a hub formed upon one of said elements and having a longitudinal bore formed therein, said hub being also formed with radially disposed openings 60 intersecting said bore, a cylindrical extension 65 formed upon the other of said elements and provided with a radially disposed bore arranged normally in alignment with said openings, a spring pressed member within said latter bore having a portion thereof extending into one of said openings and in yielding engagement therewith, said member serving to connect said hub with said extension for rotation therewith and acting as a release therefor upon undue rotative strain imparted to one of said elements, a groove and pin connection between the hub and said extension for preventing longitudinal separation of the latter with respect to said hub, and a bearing 70 for receiving said hub having a length substantially equal to that of the hub and serving as a covering for said connection. 75 2. In combination with a bearing for the support of a rotatable member, of a hub formed upon said member and received within said bearing, said hub being provided with a longitudinal bore and a pair of radially disposed openings intersecting said bore, a cylindrical extension formed upon an associated operating member having a radially 80 disposed bore formed therein arranged normally in alignment with said opening, a spring pressed ball within said bore having a portion thereof extending into one of said openings and in yielding engagement therewith, said ball serving to connect said hub with said extension for rotation therewith and to act as a release therefor when undue strain is imparted to one of said members, and a groove and pin connection between the 85 hub and said extension for preventing longitudinal separation of the latter, said groove and pin connection and said openings being covered by the provision of said bearing. 90 95 In testimony whereof I affix my signature. 100 105 GEORGE E. NORRIS.
